UNITED STATES PATENT OFFICE

HENRY R. NAYLOR, OF DERBY, CONNECTICUT, ASSIGNOR TO THE H. A. MATTHEWS MANUFACTURING COMPANY, OF SEYMOUR, CONNECTICUT, A CORPORATION

TOGGLE BOLT FOR TRUNKS AND OTHER LUGGAGE, ETC.

Application filed October 10, 1930. Serial No. 487,782.

This invention relates to an improvement in toggle-bolts of the type particularly adapted for use in holding the hinged members of trunks, suitcases, and other luggage in their closed positions, though available for use in a variety of situations.

The main object of this invention is to provide a convenient and reliable device of the class referred to, constructed with particular reference to security and relative ease of operation.

With the above and other objects in view as will appear from the following, my invention consists in a toggle-bolt for trunks and other luggage, etc., having certain details of construction and combinations of parts as will be hereinafter described and particularly recited in the claims.

In the accompanying drawings:

Fig. 1 is a face view of a toggle-bolt embodying my invention and shown in its fully-latched position;

Fig. 2 is a view thereof in side elevation;

Fig. 3 is a view thereof in longitudinal section taken on the line 3—3 of Fig. 1;

Fig. 4 is a longitudinal sectional view corresponding to Fig. 3 but showing the parts in the positions due to them when the toggle-lever is moved slightly away from its fully-latched position to initiate the unlatching of the parts;

Fig. 5 is a corresponding view but showing the parts in the positions due to them when the toggle-link and toggle-lever have been swung to their fully-retired positions;

Fig. 6 is a face view of the mounting-plate detached;

Fig. 7 is an edge view thereof;

Fig. 8 is a face view of the latch-plate detached;

Fig. 9 is an edge view thereof;

Fig. 10 is a face view of the toggle-lever detached;

Fig. 11 is an edge view thereof;

Fig. 12 is a face view of the toggle-link detached; and

Fig. 13 is an edge view thereof.

The particular toggle-bolt herein chosen for the illustration of my invention consists, as shown, of a struck-up sheet-metal mount-

ing plate 15 provided with the usual countersunk holes 16 for the reception of rivets, etc., and at its straight lower edge 17 with an integral upstanding resilient detent-finger 18 which is bent to provide a transverse detent-notch 18^a.

Struck up from the body of the mounting-plate are a pair of complementary spaced-apart ears 19 arranged parallel with each other and perforated for the reception of a pivot-pin 20 which also extends through the upper ends of the perforated side-flanges 21—21 of a substantially-channel-shaped sheet-metal toggle-link 22, the said flanges of which fit over the respective outer faces of the ears 19 just above described and as shown in Fig. 1 of the drawings.

Extending transversely between the side-flanges 21—21 of the toggle-link 22 about midway the length thereof is a detent-pin 23 adapted to coact with the resilient detent-finger 18 of the mounting-plate 15 for the purpose as will hereinafter appear. The free end of the pivotal toggle-link 22 is provided with a transverse pin 24 upon which is pivotally mounted between its ends a toggle-lever 25 terminating at its outer end in a finger-piece 26 and having its side-walls 27—27 perforated for the free passage of the pin 24. The inner end of the toggle-link 25 is offset at an angle to form a resilient latching-finger 28 bent over at its outer end to form a cylindrically-contoured latching-nose 29 adapted to fit beneath the hooked outer end 30 of a resilient latching-abutment 31 formed integral with and offsetting at an angle from a struck-up sheet-metal latch-plate 32 near the upper edge thereof. The said latch-plate 32 has a substantially-straight upper edge 32^a mating with the lower edge 17 of the mounting-plate 15, and is provided with the usual countersunk holes 33.

The portion of the toggle-lever 25 lying at the base of the resilient latching-finger 28 is rounded, as shown, to form a lifting-nose 34 engaging with the front face of the latch-plate 32 for the purpose as will hereinafter appear when the toggle-lever is rocked by means of its finger-piece 26 toward its unlatched position.

In its fully-latched position, as shown in Figs. 1 to 3 inclusive, the detent-pin 23 is engaged with the detent-notch 18^a in the resilient detent-finger 18 of the mounting-plate and tends to retain the parts in the positions in which they are shown in the figures just referred to. In this position, also, the latching-nose 29 of the toggle-lever 25 is hooked beneath the cylindrically-contoured terminal 30 of the latching-abutment 31 so that the mounting-plate 15 and the portion of the luggage secured thereto is drawn toward the latch-plate 32 and the portion of the luggage to which it is secured. It is understood that in usual practice, the mounting-plate 15 is secured to one section of a hinged trunk or similar article, while the latch-plate 32 is secured to the face of the complementary hinged-member.

With the parts in their fully-latched positions, as shown in Figs. 1 to 3 inclusive, they are substantially proof against accidental displacement and rattling not only by the engagement of the latching-finger 28 with the latching-abutment 31 but by the engagement of the detent-pin 23 with the detent-finger 18.

When the finger-piece 26 of the toggle-lever 25 is lifted to unlatch the mounting-plate 15 from the latch-plate 32, the terminal 29 of the latching-finger 28 will tend to ride from under the hooked terminal 30 of the latching-abutment 31 and at the same time the lifting-nose 34 of the said toggle-lever will be engaged with the front face of the latch-plate 32 to pry the toggle-link 22 outward so as to disengage its detent-pin 23 from the detent-notch 18^a in the detent-finger 18 of the mounting-plate 15. This initial undertaking movement is illustrated in Fig. 4.

The continued outward swinging movement of the toggle-lever 25 away from the latch-plate 32 will effect the complete disengagement of the latching-finger 28 from the latching-abutment 32 and also effect the complete disengagement of the detent-pin 23 from the detent-finger 18, so that the parts may be swung into the positions shown in Fig. 5, in which the latch-plate 32 is uncoupled from the mounting-plate 15 and one or the other of the said plates may be moved away from the other as the natural result of the opening of a trunk or similar container.

In the fully-latched positions of the parts it will be noted that the coaction of the detent-pin 23 with the detent-finger 18 serves to hold them in such position so that they are not readily displaced and affords a safety feature in addition to the natural tendency of the toggle-members to remain in their closed position. Furthermore, the lifting-nose 34 of the toggle-lever being a relatively-short distance from the pivot-pin 24 affords a very powerful leverage when the relatively-distant finger-piece 26 is lifted to disengage the detent-pin 23 from the detent-finger 18.

It will be understood by those skilled in the art that my invention may assume varied physical forms without departing from my inventive concept, and I, therefore, do not limit myself to the specific embodiment herein chosen for illustration, but only as indicated in the appended claims.

I claim:

1. In a device of the class described, the combination with a toggle-link; of a mounting-plate to which the said toggle-link is pivotally connected; a detent-member carried by the said mounting-plate; a complementary detent-member carried by the said toggle-link in position to engage the first-mentioned detent-member when the parts are in their fully-latched positions; and a toggle-lever pivotally connected between its ends to the said toggle-link for forcibly disengaging the aforesaid detent-members one from the other. 75 80 85

2. In a device of the class described, the combination with a toggle-link; of a mounting-plate to which the said toggle-link is pivotally connected; a detent-member carried by the said mounting-plate; a complementary detent-member carried by the said toggle-link in position to engage the first-mentioned detent-member when the parts are in their fully-latched positions; and a toggle-lever pivotally connected to the said toggle-link 90 95 and provided with a lifting-nose for forcibly disengaging the aforesaid detent-members one from the other.

3. In a device of the class described, the combination with a sheet-metal toggle-link 100 of U-shaped form in cross-section; of a mounting-plate to which the said toggle-link is pivotally connected; a sheet-metal toggle-lever also of substantially U-shaped form in cross-section and forming a prolongation of the and fitting within the U-shaped form of the said toggle-link to which it is pivotally connected between its ends; a latching-nose carried by the said toggle-lever at its inner end; and a latch-plate adjacent the said mounting-plate and carrying a latch-abutment located in position to be engaged by the said latching-nose. 105 110 115

4. In a device of the class described, the combination with a toggle-link; of a mounting-plate to which the said toggle-link is pivotally connected; a detent-finger carried by the said mounting-plate; a detent-bar carried by the said toggle-link in position to engage the said toggle-finger when the parts are in their fully-latched positions; and a toggle-lever pivotally connected to the said toggle-link and provided with a lifting-nose for forcibly disengaging the said detent-bar from the said detent-finger. 120 125

5. In a device of the class described, the combination with a toggle-link; of a sheet-metal mounting-plate to which the said toggle-link is pivotally connected; an integral detent-finger struck up from the said sheet- 130

metal mounting-plate; a detent-bar carried by the said toggle-link in position to engage the said detent-finger when the parts are in their fully-latched positions; and a toggle-
5 lever pivotally connected to the said toggle-link and provided with a lifting-nose for forcibly disengaging the said detent-bar from the integral detent-finger of the said mounting-plate.

10 In testimony whereof, I have signed this specification.

HENRY R. NAYLOR.
